UNITED STATES PATENT OFFICE.

JOHN F. KOMP, OF CHICAGO, ILLINOIS.

LOUNGE-FRAME.

SPECIFICATION forming part of Letters Patent No. 252,604, dated January 24, 1882.

Application filed November 14, 1881. (No model.)

To all whom it may concern:

Be it known that I, JOHN F. KOMP, a citizen of the United States, residing at Chicago, in the county of Cook and State of Illinois, 5 have invented a new and Improved Lounge-Frame, of which the following is a specification.

The object of my invention is to produce a stronger and better lounge frame than that which has hitherto been in use, with a greater 10 economy in the use of material.

Figure 1 is a perspective view of the frame. Fig. 2 is a sectional view of one of the side pieces of the frame.

Similar letters refer to similar parts throughout the several views.

Lounge-frames hitherto in use have always been made with the foot-piece of one or more separate pieces, and the side pieces also separate, sometimes covered with one continuous 20 strip of veneering extending around the two sides and the foot.

My invention consists in making the two sides and foot of the lounge-frame of one con-

tinuous strip or piece of wood *b*, Fig. 1, with a smaller continuous strip, *a*, attached to it. 25 A cross-section, at *x x*, Fig. 1, is shown in Fig. 2, showing the relative position of *a* and *b* to each other, *a* and *b* being bent in the middle, and their extremities attached to the cross-piece at the head of the lounge, make a stronger and a better frame for the lounge and afford fewer crevices for insects, and in manufacturing cause less wastage of material than a frame manufactured in the old way. The strips or pieces of wood *a* and *b* are bent by 30 steaming and dried in a bent position. 35

What I claim is—

In a lounge-frame, the bent piece of wood *b*, forming the two sides and the foot of the frame, for the purpose specified, substantially as set 40 forth.

JOHN F. KOMP.
